JOHN C. RAMSEY, OF SUFFOLK, VIRGINIA, ASSIGNOR TO RAMSEY PACKAGE CORPORATION, OF SUFFOLK, VIRGINIA, A CORPORATION OF VIRGINIA

WOOD TRIMMING OR EDGING MACHINE

Application filed October 18, 1927. Serial No. 226,948.

This invention relates to wood trimming or edging machines and more particularly to machines for severing the rough edges from objects, such as barrel staves.

5 An object of the invention is to provide a machine of this type wherein a plurality of superimposed barrel staves or other flat longitudinal members may be trimmed along their edges in a single operation.

10 Further the invention provides means whereby the completed staves are caused to fall upon a chute from whence they are discharged into a suitable receptacle placed to one side of the machine.

15 The invention also contemplates a stave trimmer whereby the staves may be expeditiously trimmed, is safe to operate and can be operated by an unskilled workman.

With the preceding and other objects and 20 advantages in mind, the invention consists in the novel combination of elements, constructions and arrangements of parts to be hereinafter specifically referred to, claimed and illustrated in the accompanying drawing, 25 wherein,

Figure 1 is an end elevation of the invention;

Figure 2 is a vertical sectional view of the same;

30 Figure 3 is a front elevation;

Figure 4 is a top plan view, and

Figure 5 is a horizontal section taken on line 5—5 of Figure 3.

Referring to the invention in detail a cast 35 metal frame 5 embodying supporting legs 6 from which vertical standards 7 arise and are connected together by horizontally extending T beams, is provided.

At their upper ends these standards are 40 formed with a pair of horizontally aligned arms 8 in which a shaft 9 is journaled, the latter carrying a large pinion 10 which is engaged by a drive pinion 11 fixed to a drive shaft 12 journaled in bearings 13 secured to the inner ends of the arms. A drive pulley 14 engaged by a drive belt 15 driven from any suitable source of power is fixed to the drive shaft at one end. A fly wheel 16 is also fixed to rotate with the drive shaft.

45 Parallel upstanding knives 17 are arranged

below the shaft 9 for trimming the longitudinal edges of superimposed barrel staves, the former being secured within a rectangular horizontally disposed frame 18 which is mounted upon horizontal brackets or extensions 19 projecting laterally from the standards at their lower ends. 55

As illustrated in Figure 2 these knives have their cutting edges disposed above the frame and each is detachably held by fastenings 20. 60

An angularly disposed chute or apron 21 is secured to the under face of the brackets or extensions with one end projecting beyond the frame 5 to catch and discharge the staves to one side of the machine as they fall 65 thru the frame 18 after the cutting operation.

A pair of reciprocable rods 22 carrying heads 23 at their lower ends are mounted in guides 24 projecting forwardly from the standards. These heads are located in vertical alignment with the knives at the ends thereof to engage the ends of a number of superimposed staves resting upon the knives. 70

To press the heads against the knives to 75 sever or trim the rough longitudinal edges therefrom connecting rods 25 eccentrically mounted upon the shaft 9 are pivotally connected as at 26 to the reciprocable rods 22.

In order to control the operation of the 80 driven shaft 9 a clutch member 27 adapted to engage a co-acting clutch member 28 fixed to the gear 10 is keyed to the shaft 9.

For the purpose of actuating the clutch member 27 a shifting arm 29 is pivotally attached as at 29^a to one of the vertical standards to swing about a horizontal axis and is operatively connected with a hand lever 30 by a rod 31. The upper end of this arm is beveled as at 32 to engage between spaced 85 lugs 33 on the clutch member 27 to shift the latter into engagement with the clutch member 28 upon rocking the hand lever in one direction.

Vertical bars or gauge elements 34 are supported rearwardly of the knives against which the stacked staves contact to correctly position the latter with respect to the knives. 95

I claim:—

1. In a stave trimming machine, a pair of parallel uprights, horizontally aligned extensions projecting therefrom, a pair of spaced knives supported from the extensions upon which a plurality of staves is adapted to be superimposed, forwardly projecting arms carried by the standards above the knives, vertically disposed gage bars depending from the arms and extending to a point to one side of one of the knives and against which the staves are adapted to be placed whereby they will be correctly positioned on the knives, tubular guides carried by the arms directly above the knives, a reciprocable rod movable in each guide, and a head carried by each rod for pressing the staves against the knives to trim the edges of the latter.
2. In a stave trimming machine, a pair of parallel uprights, horizontally aligned extensions projecting therefrom, a pair of spaced knives supported from the extensions upon which the staves are adapted to be superimposed, forwardly projecting arms carried by the standards above the knives, tubular guides carried by the arms directly above the knives, a reciprocable rod movable in each guide and a head carried by each rod for pressing the staves against the knives.

Signed at Suffolk, in the county of Nansemond and State of Virginia, this 15th day of October, A. D. 1927.

JOHN C. RAMSEY.
